UNITED STATES PATENT OFFICE

VIOLA BARNARD, OF LOS ANGELES, CALIFORNIA

DESIGN FOR A STORE FRONT

Application filed April 18, 1930. Serial No. 35,308. Term of patent 14 years.

To all whom it may concern:

Be it known that I, VIOLA BARNARD, a citizen of the United States, and a resident of the city of Los Angeles, county of Los Angeles, and State of California, have invented a new, original, and ornamental Design for a Store Front, of which the following is a specification, reference being had to the accompanying drawings, forming part thereof, in which—

Fig. 2 is a cross sectional view of the mounting taken along the plane 2—2 of Fig. 1; and Fig. 3 is a fragmentary side elevational view in reduced scale of my store front.

I claim:

The ornamental design for a store front substantially as shown.

VIOLA BARNARD.
